ATTORNEY

UNITED STATES PATENT OFFICE.

VERNER CLINTON SMITH, OF SALINA, KANSAS.

COPYHOLDER.

Application filed October 23, 1924. Serial No. 745,461.

To all whom it may concern:

Be it known that I, VERNER C. SMITH, a citizen of the United States, residing at Salina, in the county of Saline and State 5 Kansas, have invented a new and useful Improvement in Copyholders, of which the following is a specification.

This invention relates to copyholders.

The object is to provide a simple, cheaply 10 manufactured and strong and durable device for holding a stenographer's pad, paper or manuscript in the proper inclined position for reading or transcribing the same.

Another object is to provide means on the 15 copy holding or supporting plate for engagement with the back cover of said pad, or the sheets of paper or manuscript, for the purpose of retaining the same upon the support in a manner to offer no interference to 20 the turning of the pages or sheets or with the reading of the stenographic notes or other matter thereon.

A final object is to provide a copy holder 25 which may be readily folded up into a compact form to occupy little space, and which may be easily and quickly set up for use by the simple engagement of a single member to properly maintain the desired inclined position without danger of collapsing.

30 A full and complete understanding of the invention may be obtained from a consideration of the following detailed description, taken in connection with the accompanying drawing forming a part of this specification, 35 it being understood that while the drawing shows a practical form of the invention, the latter is not to be confined to strict conformity with the showing thereof, but may be changed or modified, so long as such 40 changes or modifications mark no material departure from the salient features of the invention, as specifically pointed out in the appended claims.

In the drawing, in which similar reference 45 characters designate corresponding parts throughout the several figures:

Figure 1 is a perspective view of the holder and showing the means for attaching a pad thereto;

50 Figure 2 is a similar view of the device looking from the rear;

Figure 3 is a side elevation of the device in folded position;

55 Figure 4 is a fragmentary plan illustrating the connection between the copy holding

plate and the prop for supporting the same in inclined position;

Figure 5 is a detail perspective view of a portion of said prop.

The improved copy holder comprises a 60 main supporting plate 1 formed of suitable sheet metal of sufficient strength and stiffness to prevent bending, said plate being of rectangular form, somewhat longer than wide, and provided along its long, side edges 65 with a plurality of spaced inturned prongs 2, preferably formed integrally with the plate, the prongs being tapered and slightly spaced apart from the surface of the plate to provide room for the side edges of the back 70 sheet 3 of a stenographer's pad 4, or other book or pamphlet.

The plate 1 is provided, at its longitudinal center line, with a longitudinally disposed slot 5 located midway between the 75 ends thereof, said slot terminating at one end in lateral enlargements providing an entrance opening 6, which is located at the bottom end of the slot when the plate is in active position, as illustrated in Figures 1 80 and 2 of the drawing.

Spaced hinge-eyes 7 are formed at the lower end of the plate 1, for interfitting relation to the corresponding eyes 8 of a base plate 9, formed of metal similar to the plate 85 1, said base being of the same width as the supporting plate 1 but only about one-half the length thereof. A hinge pin 10 is passed through the aligned eyes 7 and 8 and the base plate is thus adapted to fold against 90 the underside of the supporting plate when desired.

At the rear edge the base plate 9 is provided with a pair of centrally-located, spaced eyes 11, between which the terminal 95 eye 12 of a prop or brace 13 formed of sheet metal, is adapted to be hinged by means of the pin 14, the said prop being of a length to be folded down upon the base plate 9 prior to the folding of the plate 1 thereon. 100

Adjacent to its free end, the prop or brace 13 is provided with opposite recesses 15 formed in its side edges to provide a laterally-disposed head 16 of the same width as the prop, and connected thereto by a neck 17 105 which is bent, as shown in Figure 5, to position the head 16 at an angle to the prop, to correspond to the acute angle of inclination of the copy-supporting plate 1. The width of the aforesaid entrance-opening 6 110

in the plate 1 is such as to readily permit the entrance of the head 16 therethrough, and the width of the neck 17 is such as to 5 freely slide along the slot 5 to the opposite or upper end thereof, when the plate is rigidly supported at said angle and will not collapse. When it is desired to fold the copy holder, it is only necessary to force the prop down along the slot 5 until the 10 head reaches the entrance opening 6, when the same may be passed therethrough, the prop folded upon the base 9 and the supporting plate 1 then folded down. The back sheet 3 of the pad may have its edges 15 readily introduced beneath the clips or prongs 2 by opening the pad, as shown in Figure 1, after which the pad proper is turned over to rest upon the supporting plate, as shown in Figure 3 of the drawing. 20 From the foregoing it will be seen that a simple, cheaply-manufactured and easily operated device has been provided, the three members constituting the structure being readily produced from suitable sheet metal 25 by simple stamping and bending processes, the same being assemblable merely by the installation of the two hinge pins to then receive a coating of enamel or like coating, to enhance the appearance of the device, and to 30 prevent rust or corrosion.

One feature of advantage is the fact that a standard shorthand pad may be inserted in place, and it is not necessary to withdraw it while taking dictation; the prop is simply 35 released and the device is put in the position shown in Figure 3, in which position the book is held firmly, and a hard, flat surface is provided on which to write.

What is claimed is:

40 1. A copy holder comprising a base plate, a copy supporting plate hinged to the base plate and adapted to be swung to an inclined position, spaced, inwardly-directed integral, pointed clips arranged along the 45 side edges of the supporting plate to overlie the front of said plate and receive the side edges of the pad or the back of the copy book, and a prop hinged to the rear edge of

the base plate and provided with a connection with the back of the copy supporting 50 plate.

2. A copy holder comprising a metal base plate; a metal copy supporting plate hinged to the front edge of the same and provided at its center with a longitudinal slot having 55 an entrance opening at the lower end, in-turned prongs formed at the side edges of the copy supporting plate for engaging the side edges of the pad or copy book, a sheet metal prop hinged at one end to the rear 60 edge of the base plate and having an integral head at its free end, said head being connected to the prop by a reduced neck and bent at an acute angle to the same to pass through said entrance opening and be 65 moved to abut the neck against the other end of the slot to hold the copy supporting plate in an inclined position with relation to said base plate.

3. A foldable copy holder comprising a 70 base plate having hinged eyes at the front and rear edges thereof, a copy supporting plate of equal width with the base plate and having hinge eyes at one end for connection with the hinge eyes at the front edge of the base plate and adapted to fold down upon the same, said copy supporting plate being longer than the base plate and having a longitudinal slot at its center provided with a transversely enlarged entrance opening at 75 the end adjacent to the front hinge, spaced in-turned prongs formed at the side edges of the copy supporting plate to hold the copy thereon, and a prop having one end hinged to the rear edge of the base plate, and provided with a head at the other end to traverse the entrance opening and engage the slot to support the copy supporting plate in an inclined position, said prop being adapted to be folded down upon the base 80 plate and beneath the copy supporting plate.

In testimony, that I claim the foregoing as my own, I have hereto affixed my signature.

VERNER CLINTON SMITH.
